UNITED STATES PATENT OFFICE.

HOWARD WEISS, OF NORTHAMPTON, PENNSYLVANIA.

INTERNAL-COMBUSTION ENGINE.

Application filed August 10, 1920. Serial No. 402,684.

My invention relates to internal combustion engines of the sleeve valve type.

The invention consists in a new and improved type of sleeve and improved means 5 for operating the sleeve, whereby the sleeve will regulate the inlet and exhaust and at the same time may be readily removed for cleaning or replacement.

Other features of my invention will be 10 more fully brought out in the following description.

Referring to the accompanying drawings in which I have illustrated my invention,—

Fig. 1 is a side elevation of an engine, 15 partly in section.

Fig. 2 is a vertical section at 2, Fig. 1.

Fig. 3 is an elevation of the complete sleeve.

Fig. 4 is a section through the sleeve showing a bracket for the sleeve actuating mechanism.

Fig. 5 is a perspective view of one of the sections of the sleeve.

Fig. 6 is an enlarged sectional view of a 25 detail of one of the combined oiling and cooling devices.

Fig. 7 is an enlarged section on line 7—7 Fig. 6.

The engine is provided with a crank case 30 *a* upon which is bolted a cylinder block *b* containing the four cylinders *h* provided with suitable water jackets 14. A crank shaft *c* carrying a fly wheel *d* is mounted in suitable bearings *e* in the crank case. Pistons *f* are 35 connected with the crank shaft by rods *g*. Within the cylinders *h* are placed the valve sleeves *i*, extending into the valve chambers 15, and in which the pistons reciprocate, made in two sections, the upper section having 40 the L-shaped ports *j*, the lower section being provided with oil grooves *k* and oil holes *l*. The sections are morticed together as at *r*, allowing a perfectly flush surface at the joint both inside and out. An annular 45 oil ring *m* fits in the lower part of the sleeve and has a cut-away portion *m'* at one side in alignment with a hole *n* in the lower part of the sleeve. The bracket *o* fits on the outside 50 of the sleeve and is provided with a tongue *p* projecting through hole *n* and filling the cut-away portion of the oil ring. Bolts *q* pass through the bracket and sleeve and engage the oil ring.

The valve chambers 15 are provided with 55 intake ports *s* and exhaust ports *t*, with which the ports *j* in the sleeves are adapted to regis-

ter in the operation of the engine. The intake and exhaust manifolds *u* and *v* are bolted to the cylinder block adjacent to the respective ports. The bolts in the upper line 60 are made with a central passage *w* which connects with passages *w'* through the cylinder block and provided at their outer ends with radial ports *x*. A valve *y* having ports *z*, adapted to register with ports *x*, is adapted 65 to fit into the ends of the bolts *w* and are provided with the levers 2 connected by means of a rod 3 leading to any convenient point, by which the valves may be manipulated. By this means, ports *x* can be adjusted 70 for the passage of air to and from the valve space 15. Oil also may be supplied for lubricating the sleeve through the hollow bolts.

The bracket *o* is provided with ears 4 to which blocks are trunnioned. Shafts 6 carried by bearings 7 are provided with cranks 8 and 9. The crank pins of cranks 8 turn in blocks 5, while the crank pins of cranks 9 are connected by side rod 11. Rod 11 is connected to the timing gears 12, of the engine, 80 by bevel gears 13.

In operation, the shafts 6 will be rotated by the rod 11 through the cranks 9, causing the cranks 8 to rotate. The rotation of cranks 8 causes the sleeves *i* to be alternately rotated 85 and raised and rotated and lowered, in a spiral motion, causing the ports *j* to register with the intake port on the intake stroke of the piston and with the exhaust port on the exhaust stroke, the ports being so arranged as 90 to be closed during the compression and power strokes. In the engine shown, two of the cranks extend in line with cranks 9 and the other two in the opposite direction, insuring the proper operation of the valve 95 sleeves.

During the operation of the engine, the valves *y* have been set to the required opening, the sleeves in their descent draw air into the valve chambers 15 through the hollow 100 bolts *w* and allow the hot air in the cooling chamber 10 to be replaced through openings 16, which afford communication between chambers 10 and 15 by the cool air entering through bolts *w*, which cools the sleeve. As 105 the sleeve rises, air is displaced by it and passes out through the hollow bolts. Oil introduced into the ports in the valve *y* will be drawn into the valve chambers as the sleeve descends.

The oil rings *m* present an annular flange 110 on the inside of the sleeves at their lower

ends, which collects and holds oil, which passes through the oil holes *l* into the oil grooves *k* to lubricate the sleeves.

It will be seen that should the upper part 5 of the sleeve become warped or scored, it may be readily replaced without the necessity of renewing the entire sleeve. At the same time, means, in addition to the usual water jackets, are provided for directly cooling the upper 10 portion of the sleeve and the valve chamber adjacent the combustion chamber, where the heat of the engine is greatest.

Further, the sleeves are positively driven from a single set of bevel gears, and any one 15 of them individually may be readily disconnected from the actuating gear by disconnecting block 5 and bracket *o* and removed through the cylinder head, without in any way disturbing the piston assembly or 20 their actuating gear.

Having now fully described my invention, what I claim and desire to protect by Letters Patent is:

1. An internal combustion engine having 25 a cylinder with a piston therein, a sleeve valve between the piston and cylinder, the inner and outer diameters throughout the

length of the sleeve being such as to pass between the cylinder and the piston, a ring engaging the inner wall of the valve at the 30 lower end thereof, a bracket connected to the outer wall of the sleeve by bolts passing through the bracket into the ring, and a valve actuating device connected to the bracket. 35

2. An internal combustion engine having a cylinder with a piston therein, a sleeve valve between the piston and cylinder, the inner and outer diameters throughout the length of the sleeve being such as to pass 40 between the cylinder and the piston, a ring engaging the inner wall of the valve at the lower end thereof having a cut-away portion 45 therein, a bracket having a tongue extending through an opening in the sleeve valve into the cut-away portion of the ring and connected to the outer wall of the sleeve by bolts passing through the bracket into the ring, and a valve actuating device connected to the bracket. 50

In testimony of which invention, I have hereunto set my hand, at Northampton, Penna., on this 30th day of July, 1920.

HOWARD WEISS.
